(57) **CLAIM**

The ornamental design for an ultrasound probe, as shown and described.

DESCRIPTION

FIG. 1 is a bottom, front, right side perspective view of an ultrasound probe showing our new design;

FIG. 2 is a bottom plan view thereof;

FIG. 3 is a top plan view thereof;

FIG. 4 is a left side elevation view thereof;

FIG. 5 is a front elevation view thereof;

FIG. 6 is a rear elevation view thereof; and,

FIG. 7 is a right side elevation view thereof.

The long dash-short dash broken lines in the figures represent boundaries of the claimed design and form no part thereof. All other broken lines represent portions of the ultrasound probe that form no part of the claimed design.

1 Claim, 3 Drawing Sheets
